UNITED STATES PATENT OFFICE.

SAMUEL STORCH, OF BROOKLYN, NEW YORK, ASSIGNOR OF ONE-THIRD TO SOLOMON E. TEPPER AND ONE-THIRD TO DAVID BERWICK, BOTH OF BROOKLYN, NEW YORK.

CONNECTOR FOR RADIO EQUIPMENT.

Application filed May 15, 1922. Serial No. 561,163.

To all whom it may concern:

Be it known that I, SAMUEL STORCH, a citizen of the United States, residing at Brooklyn, in the county of Kings and State 5 of New York, have invented certain new and useful Improvements in Connectors for Radio Equipments, of which the following is a full, clear, and exact specification.

This invention relates to connectors for 10 radio equipment, and especially to connectors for what are commonly known in this art as three coil mountings.

It is the object of the present invention to provide an improved and simplified form of 15 connector mounting of bracket having a plurality of connector blocks to which the three coils of a radio outfit may be attached. This invention, however, has to do with the construction of the connector bracket and 20 the mounting of the blocks therein rather than with the means of attaching the coils to said blocks, so that it is deemed unnecessary to illustrate the coils.

The invention will be first hereinafter described in connection with the accompanying drawings, which constitute part of this specification, and then more specifically defined in the claims at the end of the description.

In the accompanying drawings, wherein 30 similar reference characters are used to designate corresponding parts throughout the several views:—

Figure 1 is a front elevation of a connector bracket made substantially in accordance with this invention, the pivoted blocks being shown parallel to the fixed central block.

Figure 2 is a broken under plan view of 40 the bracket, the position of one of the pivoted blocks when swung outward away from the fixed block being indicated in dotted lines, and

Figure 3 is a fragmentary end view of the bracket showing the clamping means for the 45 trunnions of the pivoted blocks more in detail.

The bracket comprises spaced members 1 and 2 between which are arranged a fixed central connector block 3 and pivoted connector blocks 6 one being arranged on each side of the fixed block. A pin 5 is passed through the fixed block and projects at either side thereof to engage the pivoted blocks and limit their movement towards said fixed 55 block.

Each of the pivoted blocks 6 has trunnions 7 engaging the spaced members 1 and 2 of the bracket for pivotally connecting them to said bracket. One of the trunnions of each of the pivoted blocks projects beyond the corresponding member of the bracket and carries a knob or handle 16 by which the block may be turned to the desired position in the bracket.

In order to retain each pivoted block in 65 adjusted position its trunnions are adapted to be clamped by slides 10 mounted in slots or ways 11 in the spaced members 1 and 2 and pressed into contact with said trunnions by screws 12 adjustably engaging 70 thimbles 14 fixed in the edge portions of said members. The trunnion engaging ends of the slides are grooved, as at 9, to constitute half journals for the trunnions and cooperate with grooves 8 in the ends of the slots or 75 ways 11, as best shown in Figure 3. The inner end of each of the adjusting screws 12 is swiveled in the corresponding slide at 15, while the outer end of said screw is preferably fitted with a milled head 13 for 80 conveniently turning the screw by hand to properly clamp the trunnion.

Each block 3 and 6 is provided with binding screws 19 for attaching the wires (not shown) which are to be connected to the coils which are also not illustrated. Said coils are designed to be detachably connected to the blocks by means of the connector studs 17 and sockets 18 in a well-known manner. The bracket may be secured to a 85 suitable support (not shown) by means of bolts 21 attached to lateral arms 20 on the members 1 and 2.

I claim:

1. In a connector, the combination with a bracket having spaced members, of a connector block mounted between said members, trunnions on said block engaging said members, means for turning the block in the bracket, a clamping slide mounted in one of said members to engage its trunnion, and means for forcing said slide against said trunnion for frictionally holding the block in adjusted position.

2. In a connector, the combination with a bracket having spaced members, of a connector block mounted between said members, trunnions on said block engaging said members, means for turning the block in the bracket, a clamping slide 105 100 105 110

mounted in one of said members and having a groove to fit around and engage its trunnion, and a screw adjustable in said members to force the slide against said trunnion for frictionally holding the block in adjusted position.

3. In a connector, the combination with a bracket having spaced members, of a plurality of connector blocks mounted between 10 said members, one block being fixed and the other pivoted to swing on the bracket relative to said fixed block, means for turning said pivoted block, and a stop extending from the fixed block at a point intermediate 15 of the spaced members for engaging the pivoted block for the purpose specified.

4. In a connector, the combination with a bracket having spaced members, of a plurality of connector blocks mounted between said members, one block being fixed and other blocks on either side of said fixed block being pivoted to swing on the bracket, means for separately turning said pivoted blocks, and a pin extending through said fixed block and projecting therefrom at opposite 20 sides to engage the pivoted blocks for limiting the movement thereof towards the fixed block.

In testimony whereof I have signed my name to this specification.

SAMUEL STORCH.
